UNITED STATES PATENT OFFICE.

SYLVAIN MATHIS, OF MORLANWELZ, BELGIUM.

REGULATOR FOR ELECTRIC LAMPS.

SPECIFICATION forming part of Letters Patent No. 372,986, dated November 8, 1887.

Application filed August 22, 1887. Serial No. 247,588. (No model.) Patented in Belgium January 27, 1887, No. 75,980; in France February 19, 1887, No. 168,854; in Luxemburg August 2, 1887, No. 867; in England August 4, 1887, No. 10,740, and in Italy August 5, 1887, No. 1,941.

To all whom it may concern.

Be it known that I, SYLVAIN MATHIS, a subject of the King of Belgium, residing at Morlanwelz, Belgium, electrician to the coal-mines 5 of Mariemont, and of Bascoup, have invented certain new and useful Improvements in Regulators for Electric Lamps, of which the following is a specification.

This invention relates to regulators for arc 10 lamps of the class in which the uniformity of the arc is obtained by the descent of the upper carbon. This motion is effected in the regulator, hereinafter described, by a lever mechanism, which, by means of a clamp, actuates 15 the carbon-holder.

In the accompanying drawings, Figure 1 is a side elevation of the improved regulator. Fig. 2 is a plan view of the same.

The said regulator comprises a bell-crank 2c lever, L L', turning upon a fixed point, O, of the lamp. In holes O', at the end of the vertical arms L' of this bell-crank lever, is pivoted a horizontal clamp-lever, E, the clamp F of which has an upper and lower shoe, which is 25 adapted to alternately embrace the carbon-holder T, placed at the center of the apparatus. The horizontal extremity of the bell-crank lever L L' is loaded with a counter-weight, P; but, instead of the latter, it may, 30 if desired, be acted upon by a spring or an electro-magnet. A third lever, constituting a double rocking lever, C D, is pivoted at the fixed points O" of the lamp, which are situated at such a height, relatively to the pivot O of the bell-crank lever, that the clamp-lever E 35 shall be between the two arms of the double rocking lever C D. The latter is provided on its left-hand arms with an armature, A, and an adjusting-screw, and on its right-hand arms 40 with a stop, D, which, by the action of a spring, R, is caused to bear against a collar, N, fixed at a suitable height upon a rod of the lamp. An arm extending from this collar is fitted with a screw, V', which makes contact 45 with a flat spring, r, thereby closing the circuit of a shunt which passes to an electro-magnet, B, arranged at a suitable distance above the armature A.

The operation of the regulator is as follows— 50 that is to say, when the lamp is not in opera-

tion, the carbons touch each other, and the extremity L of the bell-crank lever L L' is kept in a raised position by a support or rod, t, arranged below the same, so that the shoes of the clamp-lever E F are removed from the upper carbon-holder, T. As soon as a current passes through the lamp it traverses an electro-magnet having coils of thick wire, which immediately separates the carbons for the formation of the arc. At the same time the extremity 55 L of the bell-crank lever L L' leaves its support t, and the counter-weight P, acting upon the said arm, presses the extremity F of the clamp-lever E F, which is consequently kept suspended in the desired position. As the 60 carbons are consumed the resistance of the arc becomes greater, which increases the power of the electro-magnet B, and the latter attracts its armature A, thus causing the rocking lever C D to swing upon its pivots O" independently 65 of the rest of the mechanism. At this moment the adjusting-screw V strikes against the extremity of the clamp-lever E, and causes the latter to swing in its turn independently of the bell-crank lever L L'. During this motion of the clamp-lever E the lower shoe of the clamp F releases the carbon-holder T, 70 while the upper shoe continues to press upon the same and causes it to descend. During the movement of the rocking lever C D the 75 flat spring is separated from the screw V', so that the current passing through the coil of the electro-magnet B is interrupted until the spring R brings the rocking lever C D back to its normal position and establishes contact 80 again. These motions continue until the normal length of the arc is restored.

All the motions of the mechanism above described are effected with such precision and sensitiveness that the differences in the length 85 of the arc cannot be detected, and the light is therefore always regular and steady.

What I claim is—

A regulator for an arc lamp, consisting of a bell-crank lever L L', pivoted at O, the arm L 95 of which is loaded with a counter-weight, P, or acted upon by a spring or an electro-magnet, while the vertical arm L' carries the lever E, provided with the clamp F, actuating the carbon-holder T, in combination with a rocking 100

lever, C D, pivoted at O", and provided at one extremity with the armature A for the electro-magnet B, and with the adjusting-screw V, acting upon the lever E, and at the other extremity with the stop D, the spring R, and also with the flat spring r, which engages with the screw V', to re-establish the derived current

passing through the electro-magnet B, substantially as described with reference to the accompanying drawings.

SYLVAIN MATHIS.
